UNITED STATES PATENT OFFICE.

MONTAGUE WILLIAM KYNCH, OF REGINA, SASKATCHEWAN, CANADA.

COMBINATION DESK AND CHAIR.

Application filed April 2, 1924. Serial No. 703,730.

To all whom it may concern:

Be it known that I, MONTAGUE WILLIAM KYNCH, a subject of the King of Great Britain, and resident of the city of Regina, 5 in the Province of Saskatchewan and Dominion of Canada, have invented certain new and useful Improvements in Combination Desks and Chairs, of which the following is a specification.

10 This invention relates to improvements in combined book-keeping desks and chairs, and the objects of the invention are to provide an efficient and economically constructed office desk of this character in 15 which a chair is readily adjusted towards or away from the desk and longitudinally of the desk.

Further objects are the provision of a 20 combined desk and chair of the character described in which the several parts will more satisfactorily perform the various functions required of them.

With the foregoing and other objects in view, the invention consists essentially in the 25 novel construction and arrangement of parts as described in the present specification and illustrated by the accompanying drawings that form part of the same.

Referring now to the drawings, in which 30 like characters of reference indicate corresponding parts in each figure:

Figure 1 is a side elevation of an embodiment of my invention.

Figure 2 is a sectional detail, partly in 35 elevation, of the rolling device for the chair.

In the drawings, A designates a desk of any suitable construction, and B a chair. The chair B is provided with castors 10 on each leg, while on the centre spar 11 of the 40 chair is a forked frame 12 adapted to fit on each side of a rail or track 13 hereinafter more fully referred to. Within the forked portion of the frame is a suitably mounted axle 14 on which a rubber-faced roller 15 45 designed, as illustrated, to contact with the surface of the rail 13, the frame 12 acting as a guide along the rail.

This rail 13 is supported on any suitable means, here shown in the form of a stand 17

with supporting legs 18, and is designed to 50 extend longitudinally of the desk and spaced therefrom, as may be arranged, so that the chair, by means of the roller contacting with the rail and casters contacting with the floor, is easily moved backwards and forwards parallel along the desk and at a predetermined distance therefrom. To adjust and retain the rail and thereby the chair at a predetermined distance from the desk, I provide extensible plates 19 fixedly secured 55 respectively to the desk and to the rail at 20 and at 21, and also provided with a thumbscrew 22 for adjustment purposes and for holding the plates when adjusted fixedly in position.

From the foregoing, the operation and advantages of my improved combination desk and chair will be apparent and it will be readily understood that the invention can be adapted to any form of desk or chair, and 70 particularly to chairs associated with drawing tables or desks of considerable length.

As many changes could be made in the above construction and many apparently widely different embodiments of my invention, within the scope of the claim, constructed without departing from the spirit or scope thereof, it is intended that all matter contained in the accompanying specification and drawings shall be interpreted as 80 illustrative and not in a limiting sense.

What I claim as my invention is:

The combination with a work element such as a desk or the like, of a guide rail movably supported above the ground and 85 parallel therewith, and adjustable extensible means connecting the work element with the rail, a chair having legs provided with castors to engage with the ground and also having intermediate the seat and said castors 90 a guideway adapted to slidably engage with said guide rail, and shock absorbing roller means carried by said guideway and engaging said guide rail.

In witness whereof I have hereunto set 95 my hand.

MONTAGUE WILLIAM KYNCH.
